UNITED STATES PATENT OFFICE

170,891

NUTCRACKER

John C. Rumsey, Lawrence, Kans., assignor of
one-half to Ferne R. Vanderhoof, Lawrence,
Kans.

Application January 26, 1953, Serial No. 23,284

Term of patent 3½ years

(Cl. D44—1)

To all whom it may concern:

Be it known that I, John C. Rumsey, a citizen of the United States, residing at Lawrence, in the county of Douglas and State of Kansas, have invented a new, original, and ornamental Design for a Nutcracker, of which the following is a specification, reference being had to the accompanying drawing, forming a part thereof.

Fig. 1 is a perspective view of a nutcracker, showing my new design.

Fig. 2 is a side elevational view thereof; and

Fig. 3 is a top plan view thereof.

I claim:

The ornamental design for a nutcracker, as shown.

JOHN C. RUMSEY.
